J. S. WILLIAMS.

Stove Grate.

No. 25,462.

Patented Sept. 13, 1859.

UNITED STATES PATENT OFFICE.

J. S. WILLIAMS, OF ST. LOUIS, MISSOURI.

GRATE.

Specification of Letters Patent No. 25,462, dated September 13, 1859.

To all whom it may concern:

Be it known that I, J. S. WILLIAMS, of St. Louis, in the State of Missouri, have invented a new and Improved Construction 5 and Arrangement of Stove-Grates; and I do hereby declare that the following is a full and exact description thereof, reference being had to the accompanying drawings, making part of this specification:—Figure 10 1, being a front elevation of a stove-grate, and a portion of the chimney in which it is placed; Fig. 2, a vertical section thereof, in the plane indicated by the line $\alpha\alpha$, Fig. 1; Fig. 3, a similar section thereof, in the plane 15 indicated by the line $\gamma\gamma$, Fig. 1; Fig. 4, a horizontal section thereof, looking upward, in the plane indicated by the line $\varepsilon\varepsilon$, Fig. 2.

Like letters designate corresponding parts in all the figures.

20 My improved stove-grate is so arranged that, while it is placed in an ordinary fire-place, it has all the advantages of a stove, in conveying the heat, produced on all sides, into the room, without any additional devices or cost; and this, combined with convenience, and readiness of application, and presenting a handsome appearance.

25 The stove-grate is placed in the ordinary fire-place C, the size of which is to be such as to furnish sufficient space in the rear, and at the top and sides of said stove-grate, for a free circulation of air.

The stove-grate A, is composed of a grate 30 B, sides, back, and register surfaces or plates D, D, extending, sidewise, sufficiently from the stove-grate body, to cover the front of the fire-place in which it is placed. The register plates D, D, are provided with perforations or open-work a, a, a, a , (Fig. 1,) 35 made in any desirable or ornamental shape, so as to allow the air to have a free circulation through the same. Register valves H, I, I, cover these perforated surfaces, both at the top and sides, except near the bottom, 40 where they are wanting, in order to allow the admission of cold air at all times. They may be opened and closed by handles h, i, i , extending through said register plates D, D, or by any other suitable means.

45 The fire-place is separated from the flue above, by a horizontal fire-board b, shown

most clearly in Fig. 4, which covers the throat of the chimney, and thereby prevents the heated air around the stove-grate, from flowing up through the flue and escaping. 55 It also prevents the soot in the chimney from falling into the fire-place. The smoke-pipe d, passes from the stove-grate, through this fireboard, into the flue. In cases where it is desirable to heat an apartment above, a 60 hot-air pipe G, is employed, extending from the fire-place up, through the flue of the chimney, and opening into the apartment above. This pipe is provided with a valve or damper g, at the lower end, having a suitable handle f, by which it is opened or closed at pleasure. By this arrangement, all superabundant heat may be utilized in heating the upper apartment, or apartments, in which a suitable register may also be provided, in the usual manner for furnaces. 65

70 The whole being thus arranged, the heat given out on all sides of the stove-grate, is secured, by conveying it out through the register plates into the room, instead of allowing it to escape up the chimney; and my improved arrangement dispenses with the use or necessity of additional backs and fixtures, by simply regulating the valves of the register plates so as to allow a free passage 75 of air. And at the same time, by means of the hot-air pipe G, and damper g, I am enabled to employ a portion of the heat for heating rooms above, thus deriving, to a certain extent, the advantages to be gained by 80 a furnace.

I do not claim the employment of a stove or grate in any manner, or connection, except when simply arranged in an ordinary fire-place, so that the fire-place itself shall 90 act as the hot-air chamber for holding and delivering the air heated by the back and sides of the grate, thereby dispensing with all complication of construction, and all additional devices; therefore

95 What I claim as my invention and desire to secure by Letters Patent, is—

The combination of the stove-grate A, having register plates D, D, and valves H, I, I, which admit unheated air from the 100 room, at all times, through the bottoms of said plates, but control the flow of heated

air into the room, as described, with the ordinary fire-place C, when the latter is separated from the flue above, by a simple fire-board b, in the manner and for the purpose of 5 poses herein specified.

In witness that the above is a true specification of my improved construction and

arrangement of stove-grates, I hereunto set

my hand this 24th day of January, 1859.

J. S. WILLIAMS.

Witnesses:

R. HOLMES,

J. B. TURNER.
